UNITED STATES PATENT OFFICE.

HENRI CHIREIX, OF PARIS, FRANCE.

SIGNALING SYSTEM AND METHOD OF SIGNALING.

Application filed August 22, 1924, Serial No. 732,500, and in France August 23, 1923.

It is a well-known fact that the loops or frames (coils) used in wireless telegraphy work for reception can also be used for transmission. It is likewise well known that 5 the 3-electrode valve may be used for obtaining alternating current of high-frequency when connected to appropriate circuits. Now, one of the objects of this invention is to utilize a loop or coil preferably 10 constituted of but one turn also as the working circuit of the valve and to thus simplify to the highest possible extent the requisite circuits in order to realize a good efficiency.

A clear understanding of the invention 15 will be had from the following description when taken in connection with the accompanying drawing in which Figure 1 illustrates a transmitting arrangement employing a frame or loop having a single turn; 20 Figure 2 represents in perspective an antenna system in the form of a prism; and Figure 3 represents the entire transmitter adapted to be used with the system shown in Figure 2.

25 Referring now to Fig. 1, element 1 is the triode, the plate of which is fed by a dynamo 2 through the choke coil 3, the filament being heated from a battery 4. The high frequency output circuit consists of the 30 blocking condenser 5 and the coil 8 closed upon the condenser 7; 6 is a condenser shunted by a grid leak resistance inserted in the grid circuit in order to reduce the mean potential during operations. The connection 9 of the grid is brought to one side of the condenser 7, the connection 10 of the filament is established at any desired point along the coil, while the connection 11 is made at any desired point at the other end 35 of the coil. The condition for maintaining sustained oscillations is more readily fulfilled as the connection 11 is made nearer the condenser; on the other hand, the energy supplied to the coil is in general increased 40 by shifting the connection 11 towards the connection 10, which has the effect of producing closer coupling between the grid and plate circuits.

The coil 8 is preferably made up of a single turn or spire made of a strip or tube of 45 conducting metal of large cross-section in order to reduce its resistance. It may be of any desired form; still the circular shape seems to be best suited, seeing that this shape, for a given surface, results in the 55 least perimeter and as a consequence a minimum of resistance for a given section. The connections 10 and 11 are preferably brought from a fixed support in the center of the coil, where connection is established 60 with the filament and plate electrodes of the tube, while the terminal contacts of 10 and 11 are shiftable along the coil.

It must be well understood that, in order 65 that self-excitation may be produced, it is necessary that the resistance of the device in order be sufficiently low in order that the high frequency current produced may give rise across the terminals of condenser 7 to a tension the value of which is in the neighborhood of that of the direct current source 2. For this reason the coil should be made 70 of a large section; the condenser 7, on the other hand, should be made of mica of high grade, or better still may be an air-condenser. 75

If in spite of these precautionary measures it should not be possible to maintain operation, a plurality of valves such as 1 may be disposed in parallel, or else valves of the 80 same power may be employed and operated at a lower voltage. In order to reduce the losses it may be desirable to connect a certain point of the coil with the ground, or else to place underneath the coil a metallic 85 lattice.

The transmitter described above will have a directional characteristic, and while this may be of advantage in certain cases, it may be a drawback in others. 90

In cases in which non-directive sending is desired, the transmitting system may consist, for instance, of three conductors placed parallel to one another in a vertical sense, such as I, II, III, in Fig. 2, and arranged 95 conformably with the generatrices of a prism the base of which is an equilateral triangle. The upper ends of these three conductors are connected together by other horizontal conductors forming the sides 100

of an equilateral triangle, and in these conductors there are inserted the capacities of the high frequency circuits (triangle mounting). The lower ends of the said three conductors are connected at a central point by other horizontal conductors (star connection). These conductors most preferably, as in the case of the simple coil or loop above referred to, are made up of tubes constituting conductors of low resistance.

In order to better understand this construction, the upper and lower planes of the prism are separately shown in Figure 3, it being understood that the vertical conductors I, II and III of Figure 2 extend respectively between I—I, II—II and III—III as indicated in dotted lines.

The three vertical conductors function and behave like three vertical antennæ; by sending three-phase currents therethrough, a rotary-field emission is obtained which can be equally well received in all directions.

This scheme is easily practiced by employing three tubes and a symmetric mounting as indicated by M. Mesny (French Patent No. 552,227). 1 stands for the dynamo, 2 are choke coils intended to prevent return flow of the high frequency oscillations, 3 are blocking condensers intended to prevent short-circuiting of the source, 4 are the three valves that are required for the three conductors I, II, and III, respectively; 5 is the battery insuring their joint heating, 6 the grid resistance of each of the said valves, 7 which is intended to lower, when in operation, the mean value of the grid potential; 8 are the capacities which conjointly with 6 insure this result; 9 finally are the condensers through which the high frequency current flows.

The reactance between the anode and the filament is given by the vertical conductors.

The reaction voltage is properly taken, as indicated, between the middle point of the lower star and the middle point of the capacities 7. It will easily be understood that it has the desired phase for the purpose of self-excitation. The system as hereinbefore described could be compared to three coils (loops) displaced by an angle of 120 degrees, all three having one common side; the said side, as to the rest, may be eliminated entirely as it is passed by a zero current (like a neutral wire in a three-phase system). In the illustration this return conductor, which is not required and therefore has been omitted, would evidently start from the middle of the star.

This comparison, as a matter of fact, will make it evident that the scheme as described is an extension of the first embodiment described.

By providing four conductors and four valves it would be possible to construct a two-phase arrangement, while with any de-

sired greater number of tubes it would be possible to obtain polyphase sending made up of a definite number of phases. It is also quite obvious that the arrangement indicated is not the only one adapted to furnish to the antenna system hereinbefore described the three-phase energy required for its operation, indeed, it is merely one of the most simple embodiments, and is here cited only by way of example.

It finally goes without saying that what is preferably under consideration here are systems of reduced dimensions, and that as a consequence the high frequency currents to be considered are of an order of 100,000 periods and over per second.

While I have shown and described various preferred embodiments of my invention I do not limit myself to the same but may employ such other modifications as come within the spirit and scope of my invention.

Claims:

1. An arrangement for the production of a revolving field especially adapted to the transmission of short waves, comprising an aerial system disposed in accordance with a three-sided prism, and a three-tube generator generating a revolving field directly in the aerial system, which constitutes at the same time the oscillation circuit.

2. In a short-wave transmission system, a plurality of vertical antennæ arranged in prismatic formation, a condenser connected between each adjacent pair of antennæ at their upper ends, a pair of condensers connected between each adjacent pair of antennæ at their lower ends, a plurality of oscillation generators, one for each vertical antenna, each having its anode circuit associated with the upper end of a corresponding antenna, and a connection from between each pair of condensers at the lower ends of the antennæ to a corresponding control electrode of each oscillation generator.

3. An arrangement for the production of a revolving field especially adapted to the transmission of short waves, including an aerial system comprising three vertical conductors disposed in accordance with a three-sided prism, a condenser connected between each adjacent pair of conductors at their upper ends, a pair of condensers connected between each adjacent pair of conductors at their lower ends, a three-tube generator associated with each vertical conductor of the aerial system, the output of each generator being connected to the upper end of a corresponding conductor, and the input of each generator being connected between each pair of condensers connecting the lower ends of said conductors.

4. In a short wave transmission system, a plurality of vertical antennæ arranged in prismatic formation, a condenser connected between each adjacent pair of antennæ at

their upper ends, a pair of condensers connected between each adjacent pair of antennæ at their lower ends, a Y connection to the antennæ at their lower ends, a plurality of oscillation generators, one for each vertical antenna, each having its anode circuit connected to the upper end of a correspond-

ing antenna, its control electrode circuit connected between a corresponding pair of condensers at the lower ends of the antennæ, and its cathode circuit connected to the midpoint of the Y connection at the lower end of the antenna. 10

H. CHIREIX.

CERTIFICATE OF CORRECTION.

Patent No. 1,702,039.

Granted February 12, 1929, to

HENRI CHIREIX.

It is hereby certified that error appears in the printed specification of the above numbered patent requiring correction as follows: Page 1, line 67, strike out the words "in order" both occurrences; and that the said Letters Patent should be read with this correction therein that the same may conform to the record of the case in the Patent Office.

Signed and sealed this 2nd day of July, A. D. 1929.

(Seal)

M. J. Moore,
Acting Commissioner of Patents.
